METHOD OF PROCESSING ELECTRICAL ELEMENTS

Norman M. Brown, Jr., Los Angeles, and Clifford A. Shank, Redondo Beach, Calif., assignors to The Garrett Corporation, Los Angeles, Calif., a corporation of California

Application September 10, 1949, Serial No. 114,936

7 Claims. (Cl. 51—281)

1

Our invention relates in general to electrical elements and a method of processing the same, and particularly relates to a method of subjecting a finished or semi-finished element to a calibration procedure.

For convenience of description the method will be described as it is applied to the calibration of electrical resistors of the type known as glass-bead thermistors, although we perceive our invention in its broader aspects as being readily adaptable to the processing of other kinds of electrical elements—capacitors, for example.

In the manufacture of these thermistors it appears to be inherent that close tolerance values are not readily obtainable. Thus a thermistor supposedly having a nominal value of 2,000 ohms at 25° C., may actually have a value anywhere between 1600-2400 ohms. That is, it is manufactured to a tolerance of plus or minus 20%, and it appears that closer tolerance values are not easily obtainable in present manufacturing processes without prohibitive cost. On the other hand, many circuit designs for the use of such elements may have calibration tolerance requirements of the order of plus or minus 1%. Particularly is this so in many electronic applications.

Another objection to wide tolerances of electrical elements is the problem of interchangeability in critical circuits. That is to say, after an electrical apparatus has been calibrated at the factory before shipment, it is particularly desirable from the standpoint of maintenance and servicing that replacement elements in the apparatus not upset the calibration of the circuit and result in unsatisfactory function after being serviced.

It is therefore a primary object of our invention to provide a simple, inexpensive method of processing electrical elements to a desired calibration tolerance.

It is a further object to provide a method of processing electrical elements of the type wherein a plurality of conductors are intimately associated with a separating medium, the said medium having a primary electrical characteristic which it is desired to change so that the element when calibrated has a final electrical response characteristic curve that is unchanged in shape or slope but which curve is confined within a desired calibration tolerance.

It is a particular object to provide a method of processing thermistors of the bead-on-glass-probe type, so that the thermistor has a final electrical response characteristic curve of unchanged shape or slope, which curve is confined within a desired calibration tolerance. Such thermistors

2

usually comprise a pair of conductors imbedded in or electrically associated with a bead of a metallic oxide semi-conductor, the whole then being enclosed in a thin glass envelope in intimate thermal contact therewith.

It is a further object to provide a method of processing glass bead thermistors and the like, whereby the response characteristic curves of the thermistors are not altered with respect to shape or slope, but are merely displaced substantially linearly with respect to one of the coordinates of the curve.

Further objects will be apparent upon consideration of the preferred embodiment of the invention shown on the drawing and described in detail herein. As aforementioned, it is contemplated that the invention is adaptable to the calibration of other electrical elements than thermistors, hence it is intended that the descriptive matter contained herein shall be interpreted as being exemplary rather than as being restrictive of the scope of the invention.

Referring to the drawing,

Fig. 1 is a greatly enlarged cross-sectional view of a glass-bead thermistor.

Fig. 2 is a cross-sectional view of a glass-bead thermistor after processing.

Fig. 3 shows one method of processing a thermistor, together with the electrical circuit used for continuous calibration; and

Fig. 4 shows characteristic curves of the thermistor before and after calibration.

In Fig. 1 a bead-on-glass-probe type of thermistor 10 is shown. Such a thermistor comprises a glass probe 11 within which are imbedded a pair of conductors 12, the ends of which are imbedded in the bead 13 comprised of a metallic oxide semi-conductor. A thin glass envelope 14 at the end of the probe 11 encloses the bead 13 and the conductors 12 for a substantial distance along their length, thereby forming a unitary probe structure having requisite strength and rigidity.

In the practice of the invention a Wheatstone bridge circuit 20 of Fig. 3 is employed for the calibration processing of the thermistor 10. Matched resistors 21 and 22 constitute the fixed arms of the bridge while a reference thermistor 23 and the thermistor 10 constitute the variable arms of the bridge. For the purpose of maintaining the reference thermistor 23 at a constant reference temperature it is desirable that this thermistor be immersed in a uniform temperature bath 24, which may be of mercury, oil or other liquid. A battery 25 is provided to supply current through a switch 26 to the bridge and a galvanometer 27 is connected to the bridge in the

well known manner through a series variable resistor 28 which is shunted by a normally-open switch 29. A switch 30 is provided to short-circuit the thermistor 10 for a purpose to be described below.

In the practice of our invention, we prefer that, for reference thermistor 23, one be selected possessing at any reference temperature the resistance at that temperature desired in the thermistor to be calibrated. That is, if it is desired to process thermistor to a nominal resistance of 1500 ohms at 100° F. within a tolerance of plus or minus 1%, then it is preferable that thermistor 23 have the value of 1500 ohms at the temperature of 100° F. It is, of course, possible to correct for minor deviation therefrom by changing the values of matched resistors 21 and 22 in a manner known to those skilled in the art.

As noted hereinabove, the calibration process comprises, in general, changing the primary electrical characteristic of the medium separating the conductors, which, in this case, involves changing the resistance of bead 13. Such a change in the primary electrical characteristic of the medium may be accomplished by changing the volume or mass of the medium. We prefer to do this by grinding the end of the thermistor 10 on a grinding wheel 31 driven by a motor 32, as shown in Fig. 3, for example. It is apparent, of course, that the reduction of the mass of the bead 13 may be accomplished in a variety of ways. For example, it may be more expedient to remove portions by drilling, or by other methods dictated by choice or circumstances.

During the grinding process the temperature of thermistor 10 will be elevated, and it is possible for its temperature to rise to such an extent, above 575° F., for example, as to permanently change the temperature-response versus resistance characteristic of the element. In order to assure against such abnormal temperature rise, our invention contemplates the use of the bridge circuit in such manner that the galvanometer will give a partial scale reading during the grinding operation, before such limiting temperature is reached, for example, at 300° F.

The preliminary bridge calibration procedure for accomplishing such use of the bridge circuit is as follows: (1) the reference thermistor 23, connected as shown, is placed in the bath 24, which is conveniently at room temperature; (2) switch 29 remains open and switches 26 and 30 are closed; (3) variable resistor 28 is adjusted so that the galvanometer 27 gives a full scale reading; (4) thermistor 10 is replaced in the bridge by a precision resistor having a resistance which is equal to that of a standard calibrated thermistor at 300° F.; (5) with switches 29 and 30 open and switch 26 closed, the reading of galvanometer 27 is noted; (6) the precision resistor is then replaced by thermistor 10.

Calibration processing of the thermistor 10 while it is in the circuit may now proceed by the grinding operation aforementioned, taking care to observe the galvanometer during the operation, and whenever the temperature of the thermistor reaches 300° F. the galvanometer 27 will give a reading like that obtained in steps (4) and (5) described above, at which time the grinding is stopped until the thermistor cools down.

Frequent checks of the progress are accomplished by dipping the thermistor 10 into the uniform temperature bath 24 and noting the galvanometer reading. As the reading approaches

zero the thermistor is approaching its specified calibration point. The switch 29 provides sensitivity of calibration without endangering the galvanometer by large bridge unbalances. Thus, as the galvanometer reading approaches zero when readings are taken, the switch 29 may be closed to provide more sensitive determination of the balance of thermistors 10 and 23. Switch 29 may be of the spring push button type in order that it will not be inadvertently left closed, and will be closed only when a sensitive reading is to be taken.

The scale of the galvanometer 27 may be graduated in percentages so as to give a direct reading of the percentage difference of resistance existing between the standard reference thermistor and the thermistor being processed. In this way, thermistors may be processed to any tolerance without changing any of the steps in the process.

It should be noted that it may be necessary to dip the thermistor 10 in a light machine oil or other suitable protective coating medium (which may be floated on the surface of the uniform temperature bath) prior to dipping it in the bath for calibration check. This is so if the bath is mercury or other liquid conductive of electricity, otherwise the conductive liquid would short across the exposed surface of the bead 13 and conductors 12 to give false readings. With respect to the uniform temperature bath 24, we wish to point out that it need be at no particular temperature, since it merely insures that the immersed thermistors 10 and 23 are at the same temperature when readings are taken.

After the calibration processing is completed the end of the thermistor which has been exposed by grinding may be given a protective coating of varnish or other suitable material. A completed element, together with its protective coating 40 may appear like that shown in cross-section in Fig. 2.

Fig. 4 shows typical exemplary characteristic curves of a thermistor before and after calibration processing. It will be noted that the curve for the calibrated thermistor is displaced substantially linearly from the uncalibrated curve. This is accomplished by changing the primary electrical value of the separating medium without changing the inherent electrical response characteristics of the element. That is to say, in the case of a thermistor it is accomplished by changing the resistance of the bead 13 without changing the shape and slope of the characteristic curve by not permitting the processing temperature of the bead to rise above its critical value.

We claim:

1. A method for the calibration processing of a first electrical element to electrical equality with a standard reference second electrical element, said first element having a critical upper temperature, said method comprising: connecting said first and second elements in an electrical circuit comparison means having indication means so arranged as to give a first indication when said first element approaches its critical temperature during the processing and to give a second indication when the processing is complete; and changing the mass of said first element without exceeding said first indication by said indication means until said second indication is given.

2. The invention of claim 1 further characterized in that said processing results in a reduction of the mass of said first element.

3. A method for the calibration processing of a first electrical element to electrical equality with a standard reference second electrical element, said first element having a critical upper temperature, said processing to be completed at a reference temperature, said method comprising: connecting said first and second elements in an electrical circuit comparison means having with indication means so arranged as to give a first indication when said first element approaches its critical temperature during the processing and to give a second indication when the processing is complete; changing the mass of said first element without exceeding said first indication by said indication means; electrically comparing said first and second elements at said reference temperature; continuing to change the mass of said first element without exceeding said first indication by said indication means; and electrically comparing said first and second elements at said reference temperature until said second indication by said indication means is given at said reference temperature.

4. A method for the calibration processing of an electrical element having a critical upper temperature, said processing being done while said element is connected in electric circuit means having an indicating means arranged to give a first predetermined indication when said electrical element reaches its critical upper temperature during the processing, and to give a second predetermined indication when the calibration process is completed, said method comprising: changing the mass of said electrical element in such manner that said first predetermined indication is not exceeded, and continuing to change the mass until said second predetermined indication is shown.

5. The invention of claim 4 further characterized in that said processing results in reduction 40 of the mass of said electrical element.

6. A method for the calibration processing of a first electrical element to a standard electrical reference at a reference temperature determined by a second electrical element, said first element having a critical upper temperature, said processing being done while both of said elements are connected in electric circuit means having an indicating means arranged to give a first predetermined indication when said first electrical element reaches its critical upper temperature during the processing, and to give a second predetermined indication when the process is completed, said method comprising: changing the mass of said first electrical element in such manner that said first predetermined indication is not exceeded; comparing electrically said first element with said second element at said reference temperature; and continuing to change the mass of said first element without exceeding said first predetermined indication until said second predetermined indication is shown at said reference temperature.

7. The invention of claim 6 further characterized in that said processing results in reduction 25 of the mass of said first element.
